FRANK Z. AHL, OF SACRAMENTO, CALIFORNIA

WALL-REGISTER CONSTRUCTION

Application filed August 6, 1929. Serial No. 333,967.

This invention relates to improvements in wall register construction, and particularly to stackheads for use in connection with hot air heating systems for homes, offices, stores or other situations where hot air is piped from a heating unit to different portions of a building.

An object of this invention is to provide a stackhead which furnishes a rigid surface transverse the wall facing material and against which rigid surface the wall surfacing material may be directly applied, and to provide a stackhead which will seal the opening in the wall against the passage of dust and soot which the present type of stackhead permits to seep out through the crevice between the stackhead and the wall surfacing material and thereby soil the face surface of the wall. Further objects are to provide, in connection with such stackhead, means whereby a register may be held in position at the stackhead outlet; to provide for use of different sized registers with standardized piping; to provide a stackhead which may be supported directly against the exterior face of the wall supporting members; to provide a stackhead which may be inserted into old building construction, as well as used in new construction, and to generally improve and simplify the present known type of stackhead.

One form which my invention may take is illustrated by my preferred embodiment shown in the accompanying drawing, to which reference is made in connection with this specification, and in which Fig. I is a vertically sectioned side elevation showing stackhead constructed with removable facing frame and register in place; Fig. II is a vertically sectioned side elevation with facing frame constructed integrally with the stackhead and without the register in place; Fig. III is a horizontal section along line 3-3 of Fig. I; Fig. IV is a horizontal section on line 4-4 of Fig. II.

A stackhead, also known to the trade as a "box," consists of the outlet and of a flue used for conveying heated air from a heating unit located at one place to an outlet at another place where the heated air is to

be used, and the most common instance is illustrated by the hot air furnace installation in homes where the conveyor pipe leads from the furnace through the walls of the building, being placed between the wall supports, and usually opening into the various rooms at the floor level, so that the lower edge of the register is flush with the floor, as shown in Fig. I. The construction shown is for this type of installation, where the register is substantially triangular in vertical cross section of side elevation, this being a standardized form of register readily obtainable and well known to the trade. My invention would be adaptable, however, to wall insert registers set above the floor level.

For protection against possible fire hazard it is usual, and in most places required by law or building regulation, that a space be provided between the heating flue or stack and the walls of the building, and this air space is a means whereby dirt, dust and soot travel from the lower floors or cellar to the heated rooms, which action is induced by the heat radiated by the stack walls. Unless the stackhead and its connection with the register is sealed tightly this dirt, dust and soot gradually sifts through any crevice between the stack and plaster or register and plaster and soils the finish of the wall surface. Numerous attempts have been made to overcome this difficulty, but many of them have resulted in very expensive and intricate structures. One of the practical difficulties of these former devices has been that provision has not been made for rigidly supporting the outlet edge of the stackhead, although placing of a groove in such outlet edge has been previously resorted to. When applying the plaster around a stackhead constructed without such grooved edges or where the edges are grooved directly on the outlet edge of the stackhead the force with which the plaster or other wall surfacing material must be applied bends those outlet edges inwardly so that when it is attempted to fit the register in place it is necessary to chip away the plaster sufficiently to straighten the outlet edge of the stackhead to receive the register, thus leaving the crev-

ice for dirt and dust to sift through. In those instances where a face frame has heretofore been used in connection with the stackhead opening there have been two very decided shortcomings; first, they have attempted to project the sheet metal of the horizontal opening of the stackhead beyond the plane of the exterior of the wall supports and clamp thereon a face frame, the result of such structure being that it can be used only on new construction, and cannot be slid up through the walls of old construction; second, they have endeavored to form a groove marginally of the face frame on the outer side of the margin of the frame instead of the inner side, resulting in closing the groove by the force of plastering thereagainst, and in order to reopen the groove to insert the register flanges, or side wings, the plaster abutting the groove must be chipped away. In an endeavor to eliminate this difficulty, some devices have added an outwardly flaring wing to the groove, extending backwardly and outwardly and nailed or secured to the wall support and imbedded in the plaster. I have eliminated these difficulties by not extending the edges of the stackhead opening beyond the surface of the wall support and by forming the face frame angularly from the stackhead opening and in relative parallelism with the surface of the wall support and by forming my marginal groove in the face of the frame inwardly. Thus the stress of plastering is directly against the outer surface of the frame and not against an unsupported side of the groove.

My invention presupposes ordinary building construction comprising vertical supporting walls and supports therefor, such as concrete, brick or the usual two inch by four inch studs, as shown at 1, the usual lathing 2 and facing plaster 5. By exterior surface of the wall support which is hereafter referred to I mean that portion which faces into a room before the finish of the lath and plaster or other wall surfacing material is applied, as indicated in the drawing 1^a. I provide a stack 6 having the usual confining walls 6^a and a cap 8^a, which stack leads from the heating unit, not shown, to the room or space to be heated. Where it is desired that registers be placed at the floor level the stack is usually constructed wider to the floor level 7 than at the continuation 8 thereof and this widening of the stack at the floor level permits the use of the type of register above described as substantially triangular in cross-sectioned side elevation. The stackhead may be supported in position by any suitable means, such as nails 9 through spacers 10; or by utilizing the facing frame 18 of my invention, the supporting nails may be driven into studs or wall support through the facing frame hereafter described as shown at 11. A standard and well known type of register 12 may be used,

having side wings or flanges 13 turned inwardly from its face and also having a slatted shutter 14 which may be opened or closed by means of a lever 14^a for the purposes, respectively, of opening and closing the register to passage therethrough. The stack 6 carries a lip or flange 15 which extends forwardly from the face of the stack on top of the floor surface and forms a snug fit with an in-turned lip of the lower longitudinal edge of the register as shown at 16. The flange 15 may be positively spaced from the floor by a boss or plate 15^a, though, since a tight fit is desirable at this point this spacing element 15^a may be eliminated and the lip 16 merely forced under the flange 15.

The substance of my invention consists, in combination with the stack 6 and the register 12, of an upper portion of the stack cut away so that the forward edges of the top and side walls forming the opening therein are in an aligned plane with the exposed surface of the supporting medium for the building walls which is shown in the drawings as studs 1, then extending said stack walls at an angle as at 17 so that the extended portion forms a flanged face frame 18 adapted to lie flat in substantially the same plane as the exposed surface of the wall supporting means, said face frame 18 extending substantially to points equal to the respective horizontal and vertical dimensions of the register, thence forming said face frame 18 forwardly for substantially the thickness of lath 2 and plaster 5 or other finishing coat, such as shown at 19, and thereat forming a narrow U-shaped groove 20, preferably by turning said face plate flange inwardly upon itself substantially to the depth of the lath and plaster and thence again turning said material forwardly upon itself substantially the same distance it was bent rearwardly, the groove thus formed adapted to telescopically receive and hold the flanges 13 of the register. Additional screws or bolts may be used to hold the register permanently in position, if desired. The face frame 18 preferably extends the entire vertical height and the horizontal length of the register and thereby forms a truss giving great rigidity to the forwardly turned flanges 19 so that the great stress of plastering against the forwardly turned flanges 19 will not cause it to bend or sag and the plaster thereagainst may be made a tight permanent junction without the necessity of having to chip it away to readjust the shape of the stackhead or the groove to fit the winged flanges 13 of the register.

My invention also provides for the use of piping of standardized size throughout a building and the adaptation of different sized registers thereto by use of the face frame 18 which may be made separate from the stackhead and joined thereto as at 17 by forming a rearwardly extending flange 21 to the face

frame 18 snugly and removably held in a groove 22 formed by turning the edges of the stackhead body back upon itself and again forwardly substantially to the wall of the face frame. This type of structure is particularly adapted to use where installation is made in old construction work and it is necessary to insert the piping through the walls, and merely remove enough plaster to accommodate the face frame 18. It will be noted that in this construction my stackhead in its lateral transverse dimension does not extend beyond the exterior surface of the wall supporting means 1^a.

Having thus described my invention, what I claim and desire to secure by Letters Patent is:

1. A device of the character described comprising a stackhead having an opening leading to a register having flanged sides, the edges of the opening of said stackhead adapted to be aligned in a plane with the exterior of a wall supporting means, a face frame angularly extending from said edges of the stackhead opening in relative parallelism with said exterior of the wall supporting means, said face frame having a flange extending forwardly and adapted to receive on the inner side thereof the side flanges of a register.

2. A device of the character described comprising a stackhead having an opening leading to a register having flanged sides, the edges of the opening of said stackhead adapted to be aligned in a plane with the exterior of a wall supporting means, a face frame extending at right angles from said edges of the opening of said stackhead in relative parallelism with said exterior of the wall supporting means, said face frame having a flanged groove extending forwardly and adapted to receive telescopically the side flanges of a register.

3. A stackhead for heating systems using wall registers, comprising a box-like portion having an inlet adapted for connection with a flue and having an opening into a space to be heated, the edges of said opening being so positioned that they do not extend beyond the plane of the exterior face of the wall supporting means, a face frame angularly extending laterally from the edges of said opening in relative parallelism with the exterior face of the wall supporting means, said face frame having a flanged groove extending forwardly adapted to receive telescopically the side flanges of a register.

4. A stackhead for piping systems using grille registers having side flanges and where-in said piping is placed into the wall of a structure, comprising a box-like portion having an inlet adapted for connection with a flue and having an opening for exhaust of a draught, the edges of said opening being so positioned that they do not extend beyond

the plane of the exterior face of the wall supporting means, a face frame extending angularly from said edges of the opening of said stackhead in relative parallelism with said exterior of the wall supporting means, 70 said face frame having a marginal forwardly extending groove formed by turning the body thereof forwardly and thence inwardly upon itself, and again forwardly, said groove adapted to receive telescopically the side 75 flanges of a register.

5. A stackhead adapted for use with a register having flanged sides, comprising a box-like structure having an inlet and an outlet opening therein, the marginal edges of the 80 outlet opening of said stackhead mounting a groove, said edges and said groove being so positioned that they do not extend beyond the plane of the exterior face of the wall supporting means, a face frame having an inwardly extending flange telescopically and snugly fitting said groove and a face plate angularly extending laterally from said stackhead opening and in relative parallelism with the exterior face of the wall supporting 90 means, and a second groove marginally of said face plate adapted to telescopically receive the side flanges of a register.
